UNITED STATES PATENT OFFICE

GEORGE S. DUNHAM, OF FORT WORTH, TEXAS, ASSIGNOR TO SOCONY-VACUUM CORPORATION, OF NEW YORK, N. Y., A CORPORATION OF NEW YORK

PROCESS FOR THE CONVERSION OF HYDROCARBONS

Application filed January 31, 1930. Serial No. 424,802.

The present application relates to processes for the conversion and distillation of hydrocarbons and has to do particularly with a process for the production, conversion, and recovery of commercial quantities of low boiling products from crude petroleum fractions, or in general from any liquid of liquefiable hydrocarbon compound or mixture which contains or is capable of producing or being converted into low boiling point hydrocarbons.

The process in its various aspects involves the production of low boiling compounds, either by separation from or conversion of higher boiling compounds, the separation of vapors containing constituents of varying characteristics, and the control of such steps.

Among the objects of this process are increases in capacity and flexibility of processes and equipment, economies in heat expenditure and attendance, increases in ease or control and length of operating period, and other aims evident from the specification.

The foregoing advantages and purposes are largely effected by means of the combinations, arrangements, and operative relationship of process steps clothed in appropriate apparatus, described and shown in the following specification and the drawing which is made a part thereof.

The drawing is a diagrammatic view, indicating a preferred combination, arrangement, and operative sequence and relation by means of which the process may be conducted. While the drawing indicates a preferred embodiment, together with certain modifications, it will be understood that the particular embodiment here shown is largely illustrative.

In the drawing, directions of flow are indicated by arrows placed upon the lines, and valves by the conventional cross mark placed upon the line valved.

Referring now to the drawing, charge oil is taken from tank 1 by pump 2, and delivered through line 3 to exchangers 4, 5, and 6, each of which is so piped that any amount of bypassing may be practiced as

desired, where it gains heat from the material with which it is therein placed in heat exchange relationship. After having been heated by heat exchange, the charge oil is delivered by line 7 into fractionator 8. In entering fractionator 8 it may enter upon one of the lower fractionating trays with which the fractionator would be equipped, or it may pass directly to the storage space provided at the bottom of such fractionators.

In the bottom of fractionator 8 the incoming fresh charge meets and is combined with the unconverted products of a cracking step later explained, which have been reduced to liquid form in fractionator 8. The combined charge and unconverted oil are withdrawn from 8 by pump 9 and passed through coils 10 in furnace 11, where the oil is subjected to cracking temperatures, while being held under a pressure sufficiently great to maintain the stream of oil at a density approaching that of a liquid. This pressure is released by valve 12 to substantially atmospheric pressure, and the products of the cracking reaction flow to vaporizer 13 where, by means of their contained heat, all products of lower boiling point than fuel oil are vaporized, to leave by vapor line 14, and enter fractionator 8. The fuel oil residue remaining in vaporizer 13 is withdrawn by line 15, passing through exchanger 6, cooler 16 and line 17 to storage.

The vapors entering fractionator 8 by line 14 consist of cracked products of the nature of the desired gasoline, gas, and the products which passed through the cracking zone without being changed. All converted and unconverted products of a boiling point higher than the desired gasoline product are condensed in fractionator 8 and dropped to the storage space in its lower portion for re-treatment.

Gasoline vapors from fractionator 8, leaving through line 18, pass through exchanger 4 and condensing coil 19 to enter drum 20. From drum 20 uncondensed gases are withdrawn by line 21, settled water is withdrawn by connection 22, a portion of gasoline is

returned by pump 23 and line 24 for the control of fractionator 8, and finished product is sent to storage through line 25. If it is desired to use any of the various processes of treating gasoline while in the vapor phase, the step may be inserted as indicated at 26 in line 18, or elsewhere. Pump 27 and line 28 serve for introducing additional cooling oil for the control of fractionator 8 from storage should the step be found necessary.

In order to better control the operation of fractionator 8 and to enable it to handle a greatly increased duty, there is withdrawn by line 29 from the bottom of fractionator 8 a portion of the oil therein. This oil is passed through exchanger 5 and cooling coil 30, whence pump 31 forces it through line 32 to be introduced into vapor line 14 just previous to its entry to fractionator 8. Thus by an extraction of heat from fractionator 8 its capacity is increased.

Uncondensed gases in line 21 contain a considerable amount of recoverable gasoline, so they are delivered preferably by means of booster 33, into absorber 34. The cool gas oil from coil 30 and pump 31 is a suitable absorbent medium for this gasoline, and so is introduced into the absorber through line 35, and when enriched is returned to the system by pump 36 and line 37, where it is preferably reintroduced to line 32 or its branches, as shown. Stripped fixed gases are removed to fuel usage by line 38. Variations in the supply of gas oil by pump 31, if in excess of requirements, may be vented by connection 39 and, if for any reason such as failure of pump, coil or exchanger, the supply should be insufficient or insufficiently cooled, a portion of the charge oil sufficient to make up the deficiency may be introduced by pump 40.

Under some conditions of operation the temperature desired at the exit from heater 45 10 may be so great that undesirable portions of the cracked fuel oil residue may be vaporized, or in extreme cases the residue may be driven to dryness, causing stoppage of the vaporizer and shut down of the equipment. This may be controlled by several means. Cooled fuel oil produced by the unit can be returned to vaporizer 13 by pump 41 and line 42, or pump 41 can handle cold fuel oil from an outside source drawn through line 43, or cool gas oil from line 32 may be introduced through line 44. The necessity for the use of any of these steps, or the particular step found best to use, varies with the stock charged and product desired, and 50 any of them, or any combination of them, may be found necessary or desirable to best operation.

As one example of the various operations that may be performed by means of this process and apparatus, an amount of 30°

A. P. I. gas oil commensurate with the size of the apparatus may be charged through the exchanger system, entering the fractionator at any temperature from atmospheric to around 500° F. depending upon the amount of exchange heating made use of. The charge, combined with material condensed in the fractionator, is heated in furnace 11 to temperatures of say approximately 900° F. at exit, and held under an exit pressure of 70 say approximately 350 pounds per square inch, the degree of temperature and pressure varying from one charging stock to another but being of the general magnitudes just stated for a 30° A. P. I. gas oil derived from North Texas crude oil. This pressure is decreased to the pressure obtaining in the vaporizer at valve 12. The pressure in vaporizer 13 is substantially atmospheric, i. e., atmospheric increased only by the resistance of apparatus between the vaporizer and final release to atmosphere, there being no constrictions or other valve or device for artificially raising this resistance. Relative to the other pressures in the system this is, for all practical purposes, substantially atmospheric.

The liquid products of the cracking reaction remaining from the vaporization and drawn off to storage amount to approximately 35% of the originally charged fresh gas oil.

From the vapor passing to the fractionator there are separated approximately 55% of gasoline-like substances and 8% of gases normally uncondensable, percentages being calculated against originally charged fresh gas oil.

In the specific example of operation given above, there is withdrawn from the bottom of the fractionator by line 29 an amount of gas oil nearly twice as great as the fresh charge which, after cooling, is divided, approximately one-third passing over absorber 34 and the rest being introduced to vapor line 14. The actual amount of this circulation will vary with the stock charged and with the equipment used, but to far greater extent with the equipment, and except in connection with the example given, is incapable of specification.

Certain of the process steps disclosed are applicable to any process of fractionation, and certain are applicable to many other processes of conversion, as well as to the one shown and described.

I claim:

1. In a process of cracking oils which comprises subjecting oil to cracking conditions of temperature and pressure in a flowing restricted stream, separating the vaporous products of the reaction stream from the liquid products thereof in a separating zone, and passing all of the vaporous products of the reaction stream simultaneously into a

fractionating zone, therein to produce a fractionator condensate liquid at the temperature existing in the bottom of the said fractionator and a fractionator overhead comprising substantially the desired products of the reaction, that step which consists of removing a portion of the fractionator condensate, cooling it sufficiently to remove a substantial portion of its sensible heat, preventing the direct return of heat so removed to the fractionator, and introducing said cooled condensate into physical admixture with the vaporous products of the reaction zone between said separator and said fractionator, thereby to cool said vapors before they are subjected to fractionation, whereby the relative volume of vapors passing upward through the equilibrium zones of said fractionator is decreased, and a fractionator of fixed vapor volume capacity is enabled to handle a relatively increased amount of desired reaction zone product.

2. The process of producing relatively low boiling point hydrocarbons from relatively high boiling point hydrocarbons which comprises passing relatively high boiling point hydrocarbons through a cracking zone and heating the same while in the cracking zone to effect a cracking of a substantial portion of the hydrocarbons, passing the hydrocarbons from the cracking zone into a separating zone and therein effecting separation of the same into vapors constituting all of the vapors produced by the heat applied to said hydrocarbons in the cracking zone and a liquid residual oil, passing the said vapors from the separating zone and into a fractionating zone as a continuously flowing stream and effecting in the fractionating zone initial fractionation of the total vapors passed from the separating zone and the condensation of higher boiling point portions thereof to form a fractionator condensate having a boiling point above the temperature existing at the bottom of the fractionating zone while the low boiling point portions of said vapors are permitted to pass through and out of said fractionating zone uncondensed, condensing and collecting the said lower boiling point portions, passing the gases and vapors which still remain uncondensed into an absorbing zone, withdrawing fractionator condensate having its boiling point above the temperature existing at the bottom of the fractionating zone from said fractionating zone, subjecting fractionator condensate thus withdrawn to cracking treatment in said cracking zone with a fresh charge of relatively high boiling point hydrocarbons, substantially continuously cooling a further portion of the fractionator condensate withdrawn from the fractionating zone to remove therefrom a substantial quantity of sensible heat, passing a portion of the fractionator condensate thus cooled into said absorbing zone into admixture with the aforesaid uncondensed gases and vapors entering said zone to absorb hydrocarbon gases and vapors and then passing the said condensate thus enriched into admixture with the vapors which have been separated in said separating zone, before said vapors are subjected to fractionation, introducing a further portion of fractionator condensate thus cooled into admixture with the vapors passed from the cracking zone above the temperature existing at the bottom of the fractionating zone, the cooling of the vapors thereby reducing the relative amount of cooling which must be effected in said fractionating operation, and reducing substantially the relative volume of vapors existent within the fractionating operation, whereby the said fractionating zone is capable of handling a substantially increased production of low boiling point hydrocarbons from the cracking zone.

3. The process of producing relatively low boiling point hydrocarbons from relatively high boiling point hydrocarbons, which comprises passing relatively high boiling point hydrocarbons through a cracking zone and heating the same while in the cracking zone to effect a cracking of a substantial portion of the hydrocarbons, discharging the hydrocarbons from the cracking zone in the form of a continuously flowing stream and separating the same into vapors constituting all of the vapors produced by the heat applied to said hydrocarbons in the cracking zone and a liquid residual oil, passing the said vapors from the separating zone and into a fractionating zone as a continuously flowing stream and effecting in the fractionating zone initial fractionation of the total vapors passed from the separating zone and the condensation of higher boiling point portions thereof to form a fractionator condensate having a boiling point above the temperature existing at the bottom of the fractionating zone while the low boiling point portions of said vapors are permitted to pass through and out of said fractionating zone uncondensed, condensing and collecting the said lower boiling point portions, passing the gases and vapors which still remain uncondensed into an absorbing zone, withdrawing fractionator condensate having its boiling point above the temperature existing at the bottom of the fractionating zone from said fractionating zone, subjecting fractionator condensate thus withdrawn to cracking treatment in said cracking zone with a fresh charge of relatively high boiling point hydrocarbons, substantially continuously cooling a further portion of the fractionator condensate withdrawn from the fractionating zone to remove therefrom a substantial quantity of sensible heat, passing a portion of the fractionator condensate thus cooled into said absorbing zone into admixture with the aforesaid uncondensed gases and vapors entering said zone to absorb hydrocarbon gases and vapors and then passing the said condensate thus enriched into admixture with the vapors which have been separated in said separating zone, before said vapors are subjected to fractionation, introducing a further portion of fractionator condensate thus cooled into admixture with the vapors passed from the cracking zone.

ing zone after the vapors have been separated from the liquid residual oil and before they are subjected to fractionation in said fractionating zone to effect a cooling of the said vapors, whereupon the previously cooled condensate is again collected in the fractionating zone together with additional condensate having a boiling point above the temperature existing at the bottom of the 10 fractionating zone, the cooling of the vapors thereby reducing the relative amount of cooling which must be effected in said fractionating operation, and reducing substantially the relative volume of vapors existent within the fractionating operation, whereby the said fractionating zone is capable of handling a substantially increased production of low boiling point hydrocarbons from the cracking zone.

15 4. The process of producing relatively low boiling point hydrocarbons from relatively high boiling point hydrocarbons, which comprises passing relatively high boiling point hydrocarbons through a cracking zone in the form of a rapidly flowing reaction stream of restricted cross sectional area and heating the same while in the cracking zone to effect a cracking of a substantial portion of the hydrocarbons, maintaining a pressure 20 upon said reaction stream of at least the order of 350 lbs. per square inch at the outlet end of the cracking zone, discharging the hydrocarbons from the cracking zone in the form of the rapidly continuously flowing 25 stream into a separating zone wherein the velocity of the said hydrocarbons is initially check and said hydrocarbons are separated into vapors and a liquid residual oil, releasing the pressure upon said hydrocarbons 30 substantially concurrently with discharge thereof into said separating zone so that the pressure in said separating zone is above atmospheric only by such an amount as is required to maintain the flow of the hydrocarbons through the remainder of the process, passing said vapors from the separating zone and into a fractionating zone as a continuously flowing stream and effecting condensation of higher boiling point portions 35 thereof to form a fractionator condensate having a boiling point above the temperature existing at the bottom of the fractionating zone while the low boiling point portions of said vapors are permitted to pass 40 through and out of said fractionating zone uncondensed, condensing and collecting the said lower boiling point portions of the vapors, withdrawing from said fractionating zone fractionator condensate having its boiling point above the temperature existing at the bottom of the fractionating zone, subjecting fractionator condensate thus withdrawn to cracking treatment in said cracking zone with a fresh charge of relatively high boiling point liquid hydrocarbons which have not previously been passed through the cracking zone, substantially continuously withdrawing a further portion of the fractionator condensate and cooling same to remove therefrom a substantial quantity of sensible heat while avoiding any direct return of the heat thus removed to the frac- 45 50 55 60 65 70 75 80 85 90 95 100 105 110 115 120 125 130

stantially continuously withdrawing a further portion of the said fractionator condensate and cooling same to remove therefrom a substantial quantity of sensible heat while avoiding any direct return of the heat thus removed to the fractionating zone, introducing fractionator condensate thus cooled into admixture with the vapors of the stream at the reduced pressure between the separating zone and the fractionating zone to effect cooling of the stream prior to its passage into the fractionating zone whereupon the previously cooled condensate is again collected in the fractionating zone with additional condensate having a boiling point above the temperature existing at the bottom of the fractionating zone, the cooling of the stream thereby reducing substantially the relative amount of cooling which must be effected in said fractionating operation, and reducing substantially the relative volume of vapors existent within the fractionating operation, whereby the said fractionating zone is capable of handling a substantially increased production of low boiling point hydrocarbons from the cracking zone.

5. The process of producing low boiling point hydrocarbons from relatively high boiling point hydrocarbons which comprises passing relatively high boiling point hydrocarbons in a stream through a cracking zone and therein effecting a cracking of a substantial portion of the same, passing the stream of hydrocarbons from the cracking zone into a separating zone and effecting separation of the same into vapors and a liquid residual oil, passing said vapors from the separating zone as a continuously flowing stream into a fractionating zone for effecting initial fractionation of the vapors and condensation of higher boiling point portions thereof to form a fractionator condensate having a boiling point above the temperature existing at the bottom of the fractionating zone while the lower boiling point portions of said vapors are permitted to pass through and out of said fractionating zone uncondensed, condensing and collecting the said lower boiling point portions of the vapors, withdrawing from said fractionating zone fractionator condensate having its boiling point above the temperature existing at the bottom of said zone, subjecting fractionator condensate thus withdrawn to cracking treatment in the said cracking zone with a fresh charge of relatively high boiling point liquid hydrocarbons which have not previously been passed through the cracking zone, substantially continuously withdrawing a further portion of the fractionator condensate and cooling same to remove therefrom a substantial quantity of sensible heat while avoiding any direct return of the heat thus removed to the frac- 100 105 110 115 120 125 130

tionating zone, introducing fractionator condensate thus cooled into admixture into the vapors of the stream between the separating zone and the fractionating zone to effect the
 5 cooling of the stream prior to its passage into the fractionating zone whereupon the previously cooled condensate is again collected in the fractionating zone with additional condensate having a boiling point
 10 above the temperature existing at the bottom of the fractionating zone, the cooling of the stream thereby reducing the relative amount of cooling which must be effected in the said fractionating operation, and
 15 reducing substantially the relative volume of vapors existent within the fractionating operation, whereby the said fractionating zone is capable of handling a substantially increased production of low boiling point hydrocarbons from the cracking zone.
